DECORATION OF FIBROUS SURFACES

Henry Freiberg, London, England, assignor of
one-half to Samuel Freiberg, London, EnglandApplication December 18, 1944, Serial No. 568,612
In Great Britain January 6, 1944

14 Claims. (Cl. 154—121)

1

This invention is for improvements in or relating to the decoration of fibrous surfaces, e. g. the surfaces of sheets of woven, knitted or felted fibres including any fibrous materials used in dress-making, leather, artificial leather, wood, paper or cardboard.

It is an object of this invention to provide a method for decorating surfaces of the kind mentioned above with materials in sheet form and with beads of synthetic resin made in situ.

According to the present invention there is provided a method for decorating a surface of fibrous material and in particular the surface of a woven or knitted fabric which method consists in applying to the said surface decorative sheet material and securing the said sheet material to the surface by means which consist of or include beads of resin formed in situ from a liquid or pasty hardenable resinous composition applied through holes in the decorative sheet material and/or to the edge of the sheet material so as to adhere both to the said sheet material and to the surface of the fibrous material.

It will be understood that the beads not only secure, or assist in securing, the decorative sheet material to the surface of the fibrous material but also contribute to the decorative effect.

The decorative sheet material may consist of any material which is reticulated, e. g. net or lace of fibrous material or gauze of metal wire. It may alternatively consist of a sheet material such as a woven fabric or a sheet of non-fibrous material, for example, cellulose ester plastic, regenerated cellulose or synthetic resin which may have had holes punched or otherwise formed in it.

The beads of synthetic resin may be formed from a resinous composition which is allowed or caused to set to a hard mass under such conditions that the decorative material and the surface to which the decoration is to be applied is not deleteriously affected. Thus, the resinous composition may have a basis of urea-formaldehyde resin but it will be understood that any type of resinous material may be employed providing it can be brought into the liquid or pasty state and can be formed into beads which set hard under conditions which do not lead to appreciable spreading of the drops. The composition may be mixed with pigments, dyes or fillers and may conveniently be applied by means of a piping bag or other apparatus employed in the decorative icing of cakes. Setting of the resin may be brought about by the addition of hardening agent to the composition and by subjecting the beaded fabric to heat.

2

The decoration may be formed of a number of elements cut in sheet material and separately attached to the surface to be decorated by the method above-described.

The invention is illustrated by the accompanying drawing in which

Figure 1 is a plan view of a textile fabric decorated in accordance with this invention;

Figure 2 shows on an enlarged scale a piece of net which may be used as the decorative element;

Figure 3 shows a piece of lace which may similarly be used as a decorative element;

Figure 4 shows also on an enlarged scale a piece of metal gauze which can be cut to form the decorative element;

Figure 5 shows a piece of sheet material, e. g. of cellulose ester, regenerated cellulose or synthetic resin which is perforated and from which the decorative elements may be cut or stamped;

Figure 6 shows on an enlarged scale one method of forming beads of resin on a fibrous surface; and

Figure 7 shows a method of employing beads for uniting two or more decorative elements to a fibrous surface.

Referring to Figure 1, 11 is a sheet of fibrous material, for example a sheet of textile fabric and 12 are decorative elements made of reticulated material and secured to the fabric surfaces by means of beads of synthetic resin 13 which adhere not only to the decorative elements but also to the fibrous surface to which they are attached. Certain of the beads 13 are applied at the edges of the decorative element while others are applied to the centre portion of the said element.

Referring to Figure 5, the sheet material 14 is perforated as at 15 and decorative elements are cut from the perforated sheet material.

In Figure 6 the fabric 16 has applied to it a bead of resinous composition which is hardenable and which is indicated by 17, the bead being applied by means of a piping bag such as is employed by confectioners in the decorative icing of cakes. The pointed end of such a piping bag is indicated at 18.

Referring to Figure 7, decorative elements 19, 20 and 21 are affixed to a sheet of fibrous material 22 by means of beads of hardenable synthetic resin, for example 24, applied to the edges and to the centre portions of the said elements. The beads applied at the centre portions not only assist in securing the decorative elements to the fibrous surface but in addition contribute to the decorative effect. The bead 25 secures the three elements 19, 20 and 21 to the fibrous surface while

the beads 26 secure two of the elements together and to the fibrous surface.

Following is a description by way of example of a method of carrying the invention into effect.

A piece of net is cut to form a decorative pattern composed of elements 12 as in Figures 1 and 7 and is applied to the surface of a piece of textile fabric 11 (Figure 1) which is to be decorated. The net is secured to the textile fabric 11 by means of droplets 13 of a pigmented heat-hardenable urea-formaldehyde resin which are applied at the edge of the net and within it so as to contribute to the decorative effect. The textile fabric with its net and bead decoration is heated in an oven at a temperature and for a time insufficient deleteriously to affect the fabric or the net but sufficient to bring about the hardening of the resin to the insoluble condition.

The decorative net and beads are so firmly attached to the fabric that the latter may be subjected to the normal processes of cleaning.

I claim:

1. A method for decorating a surface of fibrous material which method consists in applying to the said surface perforated decorative elements of sheet material and securing the said elements to the said surface by means which include decorative beads of synthetic resin formed in situ from a pasty hardenable resinous composition applied through holes in the decorative elements and to the edges of the said elements so as to adhere both to the said elements and to the surface of the fibrous material to be decorated and thereafter causing the resinous composition to harden without substantial flattening so as to produce hardened upstanding decorative beads of resin.

2. A method for decorating a surface of fibrous material which method consists in applying to the said surface a plurality of decorative elements of net laid in contact with the said surface and securing the net to the said surface by applying droplets of hardenable synthetic resinous composition to the net so as to adhere both to the net and to the surface of the fibrous material and thereafter hardening the droplets of the resinous composition to form upstanding decorative beads.

3. A method for decorating a surface of fibrous material which method consists in applying to the said surface a plurality of decorative elements of lace and securing the said elements to the fibrous material by means of drops of hardenable synthetic resin applied through interstices in the lace to the fibrous material so as to secure the lace to the said fibrous material and thereafter causing the synthetic resin to harden to form upstanding decorative beads.

4. A method for decorating a surface of fibrous material which method consists in applying to the said material decorative elements consisting of woven fabric having holes punched therethrough and securing the said elements to the said fibrous material by decorative beads of synthetic resin formed in situ from a hardenable resinous composition applied through at least certain of the holes in the decorative element so as to adhere both to the said element and to the surface of the fibrous material to be decorated and thereafter causing the resinous composition to harden to form upstanding decorative beads.

5. A method for decorating a surface of textile material which method consists in applying to the said surface decorative elements also of textile material and securing the said decorative elements to the said surface by means which include

decorative beads of synthetic resin formed in situ from a hardenable resinous composition applied as droplets through holes in the decorative elements and to the edges of the said elements so as to adhere both to the said elements and to the surface of the textile material to be decorated and thereafter causing the resinous composition to harden to form upstanding decorative beads.

6. A method for decorating a surface of fibrous material which method consists in applying to the said fibrous material decorative elements of metal gauze and securing the said elements to the said fibrous material by means which include decorative beads of synthetic resin formed in situ from a pasty hardenable resinous composition applied as globules through holes in the decorative elements and to the edges of the said elements so as to adhere both to the said elements and to the surfaces of the fibrous material to be decorated and thereafter causing the globules of the resinous composition to harden to form upstanding decorative beads.

7. A method for decorating a surface of fibrous material which method consists in applying to the said surface decorative elements of reticulated sheet material and securing the said elements to the fibrous surface by means of decorative beads of synthetic resin formed in situ from a pasty hardenable resinous composition applied at the edges of the said decorative elements while in the unhardened condition so as to adhere both to the said elements and to the surface of the fibrous material to be decorated and thereafter causing the globules of resinous composition to harden to form upstanding decorative beads.

8. A method of decorating a surface of a textile fabric which method consists in applying to the said surface decorative elements of fabric and securing the said elements to the said textile surface by means which include decorative beads of synthetic resin formed in situ from a pasty hardenable resinous composition applied in the unhardened form so that at least two of the decorative elements are secured together and to the surface of the textile material to be decorated by at least one decorative bead and thereafter causing the resinous composition to harden to form the upstanding decorative beads.

9. A method for decorating a surface of fibrous material which method consists in applying to the said surface decorative elements of non-fibrous perforated sheet material secured to the fibrous material by means of decorative globules of hardenable synthetic resin while in the unhardened state, the said globules being applied through perforations in the decorative elements so as to adhere to the said elements and to the surface of the fibrous material and thereafter causing the globules to set and harden to form upstanding decorative beads.

10. A method for decorating a surface of fibrous material which method consists in applying to the said surface decorative elements of sheet material made of a substance selected from the group consisting of cellulose ester plastic, regenerated cellulose and synthetic resin and securing the said elements to the said fibrous surface by means which comprise decorative beads of synthetic resin formed in situ from a pasty hardenable resinous composition applied through holes in the decorative elements so as to adhere both to the said elements and to the surface of the fibrous material to be decorated and thereafter causing the resinous composition to harden to form the decorative beads.

11. A fibrous material having surface decoration comprising reticulated material secured to the surface of the fibrous material by means of decorative hardened self-adherent and upstanding globules of synthetic resin.

12. A textile fabric bearing on its surface decorative elements secured to the said surface by upstanding decorative hardened beads of synthetic resin adhering both to the edges of the decorative elements and to the surface of the 10 textile fabric.

13. A textile fabric decorated with elements of non-fibrous material consisting of sheet material selected from the group consisting of cellulose ester plastic, regenerated cellulose and synthetic resin secured to the said textile material by decorative beads of hardened synthetic resin upstanding from the surface of the decorated fabric at least certain of which decorative beads

contact both the non-fibrous decorative elements and the textile material.

14. A fabric bearing surface decoration consisting of elements of reticulated sheet material lying against the said textile material and secured thereto by decorative upstanding beads of hardened synthetic resin adhering both to the said elements and to the surface of the textile fabric.
